(57) **CLAIM**

The ornamental design for a user interface for a computer display, as shown and described.

DESCRIPTION

The FIGURE is a front view of a user interface for a computer display showing our new design.

The broken line drawing of the computer screen is for illustration only, and forms no part of the claimed design. The broken line showing of images in windows and the areas there within form no part of the claimed design. The words, letters, numbers, shadings, and various graphical representations are for illustrative purposes only and form no part of the claimed design.

The broken line showing of text is included for the purpose of illustrating unclaimed portions of the user interface for a computer display and forms no part of the claimed design.

1 Claim, 1 Drawing Sheet
